UNITED STATES PATENT OFFICE.

LAWRENCE DINKELSPIEL, OF WEST NEW YORK, NEW JERSEY, ASSIGNOR TO DINKELSPIEL & CO., INC., OF WEST NEW YORK, NEW JERSEY, A CORPORATION OF NEW JERSEY.

DESIGN FOR LACE.

Application filed April 12, 1927. Serial No. 21,562. Term of patent 3½ years.

To all whom it may concern:

Be it known that I, LAWRENCE DINKELSPIEL, a citizen of the United States, residing at West New York, county of Hudson, and State of New Jersey, have invented a certain new, original, and ornamental Design for Lace, of which the following is a specification, reference being had to the accompanying drawing, forming part thereof.

The figure is a plan view of lace showing my new design, the opposite end of the structure being a repetition of the end illustrated.

I claim:

The ornamental design for lace, as shown and described.

LAWRENCE DINKELSPIEL.
